SPIDER

Spencer W. Long, Redondo Beach, Calif., assignor
to The National Superior Company, Toledo,
Ohio, a corporation of Delaware

Application March 5, 1935, Serial No. 9,373

13 Claims. (Cl. 24—263)

This invention relates to spiders, and more particularly to a spider or construction designed for the handling of long strings of tubing or pipe in well drilling, cleaning or maintaining operation.

5 It is an object of this invention to provide a spider which is of such construction as to enable a single individual to set or release the slips with one hand and in which construction the slip 10 operating parts, with the exception of the operating lever therefor, are totally enclosed.

Another object of this invention is to provide a spider in which there is provided a means for maintaining the slips of the spider at all times 15 yieldably urged into the position desired for the slips to occupy, that is, either in the gripping or the retrieved positions.

Another object of this invention is to provide a spider, including a pair of opposed slips for the 20 gripping of pipe or tubing in which the slips are so mounted as to be maintained substantially vertical during all positions of their operation.

Another object of this invention is to provide a spider for the handling of tubing or pipe, which 25 spider includes opposed slips so positioned and supported that their center of mass at all times tends to rotate the slips with reference to their support into a position out of the vertical and in which construction there are provided riding 30 surfaces against which the complementary riding surfaces of the slips engage to resist the tendency of the slips to rotate from the vertical to thereby maintain the slips at all times in substantially vertical position.

35 Other objects and advantages of this invention it is believed will be apparent from the following detailed description of a preferred embodiment thereof as illustrated in the accompanying drawings.

40 In the drawings:

Figure 1 is a top plan view partly in horizontal section of a spider embodying my invention.

Figure 2 is a sectional side elevation taken substantially on the line 2—2 of Figure 1.

45 Figure 3 is a side elevation of the spider embodying my invention with one of the housing plates removed.

Figure 4 is a side elevation opposite to that illustrated in Figure 3.

50 Figure 5 is a sectional side elevation similar in character to Figure 2 illustrating the slips as moved to the retrieved position.

Figure 6 is a figure similar to Figure 3 illustrating the position of the operating mechanism 55 in supporting the slips in the retrieved position.

Figure 7 is a diagrammatic view illustrating the modified form of construction embodying my invention wherein the slips are maintained in substantially vertical position at all times during their movement.

Figure 8 is a sectional side elevation similar to Figure 2 of a modified form of spider embodying my invention illustrating a further modification of the means provided for maintaining the slips at all times in substantially vertical position.

Figure 9 is a sectional view taken substantially on the line 9—9 of Figure 8.

In the preferred embodiment of my invention as illustrated in the accompanying drawings, 15 indicates the body of the spider in which there is mounted opposed slips 2 and 3. The body is formed with a central opening providing a slip engaging seat 4 upon which the slips are seated in the gripping position as illustrated in Figure 2. 20

Means are provided for actuating the slips 2 and 3 to the gripping position as illustrated in Figure 2 from the retrieved position as illustrated in Figure 5 and for actuating the said slips in the reverse direction, which means are 25 preferably of the following construction:

Mounted transversely of the body 1 are shafts 5 and 6, which shafts are rigidly mounted in position. Journaled upon the shafts 5 and 6 are sleeves 7 from which there is formed actuating arms 8. The actuating arms 8 are pivotally connected by a slot and pin connection 9 and 10 with each of the slips 2 and 3. The sleeve 7 on the shaft 6 is formed with an arm 11, and the sleeve 7 on the shaft 5 is provided with a 35 similar arm 12 between which arms 11 and 12 a connecting link 13 is provided. The arm 12 is formed to receive and accommodate an actuating handle 14 which extends exteriorly of the body 1 to a position where it may be gripped for actuation by an operator of the device.

In order to maintain the slips 2 and 3 either in retrieved or gripping position at all times as desired, the following means are preferably provided:

Mounted between the pivot pin 15 connecting the arm 11 and the link 13 and a stationary abutment 16 of the body 1 is a spring 17. Similarly positioned between a pivot pin 18 which connects the arms 12 and the link 13 and a stationary abutment 19 of the body 1 is a second spring 20.

The springs 17 and 20 are so positioned with relation to the centers 21 and 22 of the shafts 5 and 6 that upon rotation of the sleeve 7 upon said shafts 5 and 6 as is occasioned through the 55

movement of the slips 2 and 3 from the retrieved position to the gripping position, or vice versa, the effective line of tension of the springs 17 and 20 passes over the centers 21 and 22 of said shafts 5 and 6 with the result that the springs 17 and 20 act to yieldably maintain the slips in the gripping position with the parts in the position as illustrated in Figure 3, and likewise act with the parts in the position as indicated in Figure 6 to maintain these slips in the retrieved position as illustrated in Figure 5.

The body 1 of the spider is provided with a vertical opening 23 through which the pipe or tubing to be gripped may be passed into the position between the slips 2 and 3 and is provided with a locking or closing bolt 24 which is passed between ears 25 and 26 of the body to maintain the spider in rigid construction and to close the opening 23 when the spider is in use or when it is desired to close the opening 23. The body 1 of the spider is formed with lifting lugs 27 and 28 by means of which the body of the spider may be handled in the well derrick.

In order to guide the pipe properly into the body of the spider, a beveled guide opening 28^a is provided in axial alignment with the center of the slip body. In order to close all of the operating parts of the spider embodying my invention, I prefer to provide closure plates 29, 30 and 31 which are releasably secured to the face of the spider by means of cap bolts 32.

The slips 2 and 3 embodied in my invention are of a construction similar to that illustrated in the patent issued to Forrest J. Young and Joseph A. Dunn for Mechanically operated slip type elevator, Patent No. 1,909,601, issued May 16, 1933, in that the slip engaging seat 4 of the body 1 is divided into two slip engaging seats 4^a and 4^b adapted to be engaged with complementary seating portions 33^a and 33^b of the slips 2 and 3 when the slips are in the gripping position as illustrated in Figure 2, and the body 1 is formed with inwardly formed recesses 34 and 35 into which said portions 33^a and 33^b of the slips move when the slips are moved to the retrieved position as illustrated in Figure 5. The body of the slips 2 and 3 is likewise formed with an inwardly formed portion 36 into which the projecting or hook intermediate portion 37 of the slip body projects when the slips are moved to the retrieved position.

The downwardly inclined face 38 of the hooked portion 37 of the body 1 is adapted to engage a complementary upwardly inclined portion 39 formed within the recess 36 of the slips 2 and 3 should the slips be moved rapidly upwardly in the bore of the body 1 so as to prevent the slips from being thrown violently upwardly in the body. As the inclined surfaces 38 and 39 engage the slips are forced to move outwardly in the body 1 from the gripping to the retrieved position, or to a position where they will no longer be engaged with the pipe mounted in the spider. Thus any tendency of the slips to be thrown upwardly within the tubing or pipe is avoided.

In order to maintain the slips 2 and 3 substantially in vertical position at all times during their movement to and from the retrieved or gripping position, or vice versa, the slips 2 and 3 are so proportioned with relation to the body and the inclined surfaces of the body 1 so that a substantially point engagement is maintained at the lower points 39^a of the slips 2 and 3 with the surface 40 of the slip body as the slips are moved to and from engaging position. The

engagement of this point 39^a with the surface 40 opposes the tendency of the slips 2 and 3 to rotate due to the position of their center of gravity being inwardly from the position of their pivotal mounting upon the pins 10.

The length of the arms 8 are so proportioned as to position the pins 10 at a point where in their movement shifting the slips to and from their gripping position in connection with the engagement of the points 39 and 40 the slips will at 10 all times be maintained substantially vertical.

In order to permit the slips to at all times seat properly upon the seat formed within the body in engagement with the tubing or pipe irrespective of the conditions or wear of the slips, positions of the concentricity or proper diametric dimensions of the pipe or tubing being gripped or the wear occasioned between the surface of the slips and the body, the slots 9 are formed in the ends of the arm 8 in such a manner that they extend almost horizontally in direction when the slips are in the gripping position illustrated in Figure 2 but extend upwardly toward the vertical as the slips are raised so that substantial vertical movement of the slips may be maintained while permitting the slips to properly seat in the bore of the body by permitting the pins 10 as carried by the slips to move inwardly along the slots 9 to accommodate for the wear or conditions as above set forth. 30

In the modified form of my invention as shown by Figure 7, similar parts are illustrated by the same numerals. This form of my invention is illustrative of the point contact that may be maintained between the lower edge 101 of the slips 2 or 3 as they travel along the surface 102 of the body 1 to maintain the slips in vertical position during their movement to gripping position from retrieved position or vice versa; the movement of the slips being indicated by the dotted lines showing partially the slips in several positions.

In the modified form of my invention as illustrated in Figure 8, similar parts are likewise illustrated by the same numerals. In this modified construction links 103 are pivotally connected to the slips 2 and 3, and the links 103 extend into the body 1 and are connected by a pin and slot connection 104 and 105 to the body 1 so that as the slips are raised or lowered they are maintained in vertical position without depending upon relative engagement of slip and body riding surfaces; the slot 105 being provided to enable the slips to properly seat on the body seat 4^b as the link 103 approaches or passes the horizontal position. 45 50 55

Having fully described my invention, it is to be understood that I do not wish to be limited to the details herein set forth, but my invention is of the full scope of the appended claims. 60

I claim:

1. In a well tube gripping device, the combination of a body having a tapered opening providing a slip-engaging seat, slips mounted within the body on the tapered seat to engage a well tube, means including a pivotedly mounted member having an oscillating movement for actuating said slips from gripping position to a retrieved position and vice versa, means including a yieldable element secured to the body and connected with said member eccentrically of its axis of rotation, said means acting to normally urge the rotation of said member in one direction to maintain the slips in engagement with the well tube when the slips are moved to the gripping position. 75

and acting to normally urge the rotation of said member in a counter direction to hold the slips in the retrieved position when the slips are moved to said latter position.

5. 2. In a well tube gripping device, the combination of a body having a tapered opening providing a slip-engaging seat, slips mounted within the body on the tapered seat to engage a well tube, means for actuating the slips from gripping 10 position to a retrieved position and vice versa, and, a means for yieldingly maintaining the slips against movement in its gripping and retrieved positions.

3. In a well tube gripping device, the combination of a body having a tapered opening providing a slip-engaging seat, slips mounted within the body on the tapered seat to engage a well tube, means for actuating the slips from gripping position to a retrieved position and vice 20 versa, and a common means for yieldingly maintaining the slips against movement in its gripping and retrieved positions.

4. In a well tube gripping device, the combination of a body having a tapered opening providing a slip-engaging seat, slips mounted within the body on the tapered seat to engage a well tube, means for actuating the slips into and out of engagement with the tube, and yieldable means operatively associated with the slips for 30 normally maintaining said slips in the gripping and retrieved positions upon the slips being moved to the gripping and retrieved positions respectively.

5. In a well tube gripping device, the combination of a body having a tapered opening providing a slip-engaging seat, slips mounted within the body on the tapered seat to engage a well tube, means for actuating the slips into and out of engagement with the tube, and yieldable means 40 operatively connected with the actuating means for normally maintaining said slips in the gripping and retrieved positions upon the slips being moved to the gripping and retrieved positions respectively.

45. 6. In a tube gripping device, the combination of a body having upper and lower tapered openings providing slip engaging faces, slips mounted in said body, said slips having upper and lower complementary tapered portions adapted to seat on the slip-engaging faces in the body when the slips are in the gripping position, the lower ends of said slips and the intermediate portion of the wall above the lowered tapered opening in the body being similarly beveled to define riding 50 surfaces for supporting and guiding said slips in the radial movement thereof, means to raise said slips, said means including a pivotally mounted lever on said body extending toward each of said slips, a slot and pin connection between the free 55 end of each of said levers and the upper end of said slips, said slot and pin connection being formed to guide the movement of the upper end of the slip in relation to the movement of the lower end of the slip so as to maintain said slip 60 substantially vertical at all times as the lower end of the slip moves upwardly and outwardly on said riding surface in the body.

7. In a tube gripping device, the combination of a body having upper and lower tapered openings providing slip-engaging faces, a slip mounted 70 in said body, said slip having upper and lower complementary tapered portions adapted to seat on the slip-engaging faces in the body when the slip is in the gripping position, means to raise 75 and lower said slip, said means including a lever

pivots supported on said body, means operatively connecting said lever with the upper end of said slip to guide said end during the radial movement of said slip, and means cooperating with the lower end of said slip to guide said slip 5 in the radial movement thereof when the slip is out of operative engagement with the slip-engaging faces in said body, said means for guiding the movement of the upper and lower ends of said slip cooperating to maintain said slip in substantially a vertical position throughout the range of said radial movement.

8. In a tube gripping device, the combination of a body having upper and lower tapered openings providing slip-engaging faces, a slip mounted 15 in said body, said slip having upper and lower complementary tapered portions adapted to seat on the slip-engaging faces in the body when the slip is in the gripping position, means to raise and lower said slip, said means including a lever 20 pivots supported on said body, means operatively connecting said lever with the upper end of said slip to guide said end during the radial movement of said slip, said lever and slip connecting means including a slot formed in one of 25 said members and a pin carried by the other of said members and positioned in said slot, said slot inclining upwardly and inwardly relative to a substantially horizontal plane including the pin axis and the lever pivotal axis when the slip is 30 in the gripping position, and means cooperating with the lower end of said slip to guide said slip in the radial movement thereof when the slip is out of operative engagement with the slip-engaging faces in said body, said means for guiding 35 the movement of the upper and lower ends of said slip cooperating to maintain said slip in substantially a vertical position throughout the range of said radial movement.

9. In a tube gripping device, the combination 40 of a body having upper and lower tapered openings providing slip-engaging faces, a slip mounted in said body, said slip having upper and lower complementary tapered portions adapted to seat on the slip-engaging faces in the body when the 45 slip is in the gripping position, means to raise and lower said slip, said means including a lever pivots supported on said body, means operatively connecting said lever with the upper end of said slip to guide said end during the radial 50 movement of said slip, said lever and slip connecting means including a slot formed in the lever, a pin in the slot and connected with the slip, said slot inclining upwardly and inwardly relative to a plane including the pin axis and the lever pivotal axis, and means cooperating with the lower 55 end of said slip to guide said slip in the radial movement thereof when the slip is out of operative engagement with the slip-engaging faces in said body, said means for guiding the movement 60 of the upper and lower ends of said slip cooperating to maintain said slip in substantially a vertical position throughout the range of said radial movement.

10. In a tube gripping device, the combination 65 of a body having upper and lower tapered openings providing slip-engaging faces, a slip mounted in said body, said slip having upper and lower complementary tapered portions adapted to seat on the slip-engaging faces in the body when the 70 slip is in the gripping position, means to raise and lower said slip, said means including a lever pivots supported on said body, means operatively connecting said lever with the upper 75 end of said slip to guide said end during the radial

- movement of said slip, and means between the upper and lower tapered openings in said body cooperating with the lower end of said slip to guide said slip in the radial movement thereof
- 5 when the slip is out of operative engagement with the slip-engaging faces in said body, said means for guiding the movement of the upper and lower ends of said slip cooperating to maintain said slip in substantially a vertical position
- 10 throughout the range of said radial movement.
11. In a tube gripping device, the combination of a body having upper and lower tapered openings providing slip-engaging faces, a slip mounted in said body, said slip having upper and lower
- 15 complementary tapered portions adapted to seat on the slip-engaging faces in the body when the slip is in the gripping position, means to raise and lower said slip, said means including a lever pivotally supported on said body, means
- 20 operatively connecting said lever with the upper end of said slip to guide said end during the radial movement of said slip, and means including a radial guide link pivoted to said body and cooperating with the lower end of said slip to
- 25 guide said slip in the radial movement thereof when the slip is out of operative engagement with the slip-engaging faces in said body, said means for guiding the movement of the upper and lower ends of said slip cooperating to main-
- 30 tain said slip in substantially a vertical position

throughout the range of said radial movement.

12. In a well tube gripping device, the combination of a body having a slip-engaging seat, a slip mounted within the body on said seat for gripping a well tube, actuating means including an element having an oscillatory movement relative to a certain axis operatively connected with the slip for actuating the slip from gripping position to a retrieved position and vice versa, and means operatively associated with the oscillating element acting to yieldably urge said element to rotate in one direction when the slip is in its gripping position, said means also acting to yieldably urge said element to rotate in a counter direction when the slip is in its retrieved position.

13. In a well tube gripping device, the combination of a body having a slip-engaging seat, a slip mounted within the body on said seat for gripping a well tube, said slip being retrievable to release said tube, an element having an oscillatory movement relative to a certain axis operatively connected with the slip, means operatively associated with the oscillating element acting to yieldably urge said slip into gripping engagement with the well tube upon the slip being moved to the gripping position, and acting to yieldably maintain said slip in a retrieved position upon the slip being retrieved.

SPENCER W. LONG. 30
